UNITED STATES PATENT OFFICE.

FRANK J. WHITTEMORE, OF MINNEAPOLIS, MINNESOTA, ASSIGNOR TO HARRY B. DYER, OF MINNEAPOLIS, MINNESOTA.

SAFE-PROTECTING DEVICE.

No Drawing.

Application filed May 16, 1923. Serial No. 639,294.

To all whom it may concern:

Be it known that I, FRANK J. WHITTEMORE, a citizen of the United States, residing at Minneapolis, in the county of Hennepin and State of Minnesota, have invented certain new and useful Improvements in Safe-Protecting Devices; and I do hereby declare the following to be a full, clear, and exact description of the invention, such as 10 will enable others skilled in the art to which it appertains to make and use the same.

My invention provides an extremely simple and highly efficient device for protecting safes that have been "blown" for the purpose 15 of robbery, and it consists of a container, preferably a glass bottle or jar, filled with or containing a liquid which, when released to the air by the breaking of the container, will produce a gas which, for a considerable 20 time, will prevent burglars or others from entering or staying in the vicinity of the blown safe.

It is a known fact that more than ninety 25 per cent of safe robberies are produced by "blowing" of the safes. The container of my safe-protecting device is suspended or supported within the safe, preferably on the inner side of the safe door, where it is bound to be broken by the force of any explosion, 30 such as would open the safe.

The smoke-producing composition is preferably a mixture of formaldehyde, glycerine and carmine. The formaldehyde gas, which constitutes the principal ingredient, when

exposed to air, penetrates the eyes, nostrils 35 and mouth, bringing tears to the eyes, causing choking and coughing and further produces a burning and smarting within the nose and throat and, in short, making it absolutely impossible for a person to stay in 40 the vicinity of the safe where the substance is released. The glycerine holds the formaldehyde in suspension and prevents the same from hugging or sticking to the upper part of the safe and causes the gas to float 45 where it will directly reach the face of the eggman or safe blower. In fact, this composition will produce an intense cloud of vapor that will float for several hours and will, for a long time, make it impossible for 50 any person to approach the safe or to stay within the vicinity of the safe. Nevertheless, the case is not a deadly gas and any person who wishes may escape simply by rapidly getting out of the way of the gas. 55

The carmine keeps the composition from deteriorating with age and to remain in solution ready for use even for years.

What I claim is:

1. A safe protecting means comprising a 60 solution made up of formaldehyde, glycerine and carmine.

2. A safe protecting device comprising a frangible container and within said container a gas-producing substance consisting 65 of formaldehyde, glycerine and carmine.

In testimony whereof I affix my signature.

FRANK J. WHITTEMORE.
